FLEXIBLE DOOR KNOB COVER

Charles J. Amdur and Edward J. Weinstein, Coral Gables, Fla., assignors to Decor Knob Cover Company, Coral Gables, Fla., a corporation of Florida

Filed May 18, 1960, Ser. No. 60,709

Term of patent 14 years

(Cl. D50—3)

FIG. 1

FIG. 2

FIG. 3

FIG. 4

FIG. 1 is a front elevation of a flexible door knob cover showing our new design.

FIG. 2 is a side elevation thereof.

FIG. 3 is a rear elevation thereof.

FIG. 4 is a cross sectional view thereof taken through section lines 4—4, FIG. 1.

The broken line portion is shown for illustrative purposes only.

We claim:

The ornamental design for a flexible door knob cover, as shown and described.
